UNITED STATES PATENT OFFICE.

CHARLES HAROLD SPOONER, OF PRINCETON, MAINE.

PUMP.

Application filed March 6, 1922. Serial No. 541,387.

To all whom it may concern:

Be it known that I, CHARLES H. SPOONER, a citizen of the United States, residing at Princeton, in the county of Washington 5 and State of Maine, have invented new and useful Improvements in Pumps, of which the following is a specification.

This invention relates to liquid pumps and proposes the construction of a hand operated pump of the reciprocating plunger type which has for its principal object the provision of means whereby the discharge nozzle of the pump may be selectively structurally associated with the body of the 10 pump so as to be conveniently manipulated by the operator of the plunger or removable from the pump body for operation at a distance therefrom.

Another object of the invention is the 20 construction of a pump in which the valves are readily accessible for cleansing purposes or for repairs.

With the above and other objects in view, my invention consists in the improved pump 25 illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is illustrated:

35 Figure 1 is a view of a pump embodying my invention shown in elevation, partly in cross section.

Figure 2 is a view in elevation taken at right angles to Figure 1.

40 Figure 3 is a detail view in cross section showing the pivotal mounting of the nozzle.

Figure 4 is a cross sectional view of the discharge nipple showing the discharge valve.

45 Figure 5 is a transverse section taken along the line 5—5 of Figure 4.

Referring in detail to the several figures the numeral 1 represents the cylindrical portion of a casing to which is attached, or 50 made integral therewith, an offset portion 2. A partition wall 3 separates the space within said casing into two parts forming a plunger cylinder 4 and a discharge chamber 5. These chambers communicate adjacent 55 their lower ends by means of a port 6.

The plunger chamber is closed at its

upper end by the flanged plug 7, which may be of wood or any suitable material having an inwardly extending portion 8 of the same diameter as the plunger chamber and 60 being secured to the casing by means of the screws 8'. The plug 7 is centrally apertured to permit the passage therethrough of the plunger rod 9.

The upper and lower ends 10 and 11 respectively of the plunger rod are slightly reduced in diameter forming shoulders 12 and 13 against which are seated the washers 14 and 15 respectively. Said washers form the stationary abutments for 70 spiral springs 16 and 17. The spring 16 is confined between the abutment 14 and a collar 18, the latter being pinned to the plunger rod 9 by means of a pin 19. The lower spring 17 is held between the washer 75 15 and the plunger 47. The object of the springs is to cushion the thrust of the plunger rod at each end of the stroke by coming resiliently into contact with the upper and lower surfaces of the plug 7. 80 The upper end of the plunger rod is provided with a transverse handle 20 which is secured in place by the screw 21 or by any other suitable means.

The plunger 47 is provided with the metallic expansion ring 22 and the follower 23 and is secured in place by the nut 24 which 85 threadedly engages the lower end of the reduced portion 11 of the plunger rod 9.

The lower end of the casing 1 is externally 90 screw threaded as shown at 25 to provide means for detachably securing thereto the strainer 26 which is formed with a screw threaded socket 27 for cooperation with the threaded lower end of the casing 1 and 95 provided with a plurality of strainer apertures 29. The lower end 30 of the strainer is imperforate and affords a base of support on which the pump is rested when in operation.

100 The strainer is provided with a partition 31 which is perforated at 32 to form an inlet opening for the plunger cylinder, said partition forming a seat for the flap valve 33 which is pivotally mounted at 34 105 in the lower end of the casing 1. A transverse bar 35 forms a stop to prevent the flap valve opening to an excessive degree.

The wall 2 of the discharge chamber 5 is provided with a discharge opening 36 which 110 communicates with a lateral nipple 37 shown in Figure 2, the latter being externally

threaded at 38, as shown in Figure 4, to which is secured the discharge nipple 39 provided with the hose connection 40. A discharge flap valve 48 is pivotally secured by means of the pin 49 to a projecting perforated lug 52 forming a part of the nipple 37 and housed within the hose nipple 39. The flap valve 48 is normally seated upon the end of the nipple 37. The flexible hose 41 is clampably secured to the hose connection 40 by means of the clip 42 and leads to the discharge nozzle 43. The vent hole 50 extending through the wall of the casing 1 near its upper end provides an air relief for that part of the plunger chamber which lies above the plunger and affords an exit for the discharge of any water which may have leaked past the plunger 47.

The casing 1 is provided on its outer surface with a threaded recess 44 shown in Figure 3 into which is secured the projecting tubular support 45 upon which is pivotally journalled the nozzle 43 by means of a projecting bracket 46 made integral therewith and provided with a cylindrical bearing aperture 51 which rotatably cooperates with said tubular support. The bracket 46 is slidably detachable from the tubular support 45 so as to permit the nozzle 43 to be carried to a point remote from the pump when occasion demands.

In operating the pump it is placed in a pail or other receptacle containing the liquid to be discharged, with the base 30 resting upon the bottom of said receptacle. The nozzle 43 may be conveniently directed at various angles of elevation by being turned upon its pivotal support by the person operating the plunger. By the provision of the detachable strainer 26 adjacent the inlet valve and the detachable hose nipple 39 adjacent the discharge valve, said valves may be conveniently reached for the purpose of cleansing or for repairs by removing said detachable fixtures. The location of the discharge opening 36 at a point below the upper closed end of the discharge chamber 5 constitutes the upper portion of said chamber an air compression chamber steadyng the stream issuing from the inlet and cushioning the impact of the working stroke of the plunger. While the specification refers to water as the liquid medium upon which the pump operates it is to be understood that it will operate equally well with any other incompressible fluid. In the case of corrosive substances such as acids or sea water the materials used in its construction must be selected with a view to the character of the substance which the pump is intended to handle.

It will be understood that various changes may be made in the form and relation of parts to suit different requirements of use, and that the invention, therefore, is not limited to the precise details of construction and arrangement shown.

Having described my invention what I claim as new and desire to secure by Letters Patent is:—

1. A pump including a plunger cylinder and a discharge chamber communicating therewith, said discharge chamber being provided with an outlet adjacent its upper end, a boss extending laterally from the plunger chamber, the axes of said boss and outlet lying in parallel planes, a nozzle journalled on said boss and a flexible conduit connecting said nozzle and outlet. 75

2. A pump including a plunger cylinder and a discharge chamber communicating therewith, said discharge chamber being provided with an outlet, a boss extending laterally from the plunger chamber, the axes of said boss and outlet lying in parallel planes, a nozzle journalled on said boss, and a flexible conduit connecting said nozzle and outlet. 85

3. A pump including a plunger cylinder and a discharge chamber communicating therewith, said discharge chamber being provided with an outlet, a boss extending laterally from the plunger chamber, the axes of said boss and outlet lying in parallel planes, a nozzle journalled on said boss and freely detachable therefrom and a flexible conduit connecting said nozzle and outlet. 95

4. A pump including a plunger cylinder and a discharge chamber communicating therewith, said discharge chamber being provided with an outlet, a boss extending laterally from the plunger chamber in a direction opposite to said outlet, a nozzle journalled on said boss and a flexible conduit connecting said nozzle and outlet. 100

5. A pump including a plunger cylinder and a discharge chamber communicating therewith at its lower end, said discharge chamber being provided with an outlet adjacent its upper end, a boss extending laterally from the plunger chamber, the axes of said boss and outlet lying in parallel planes, a nozzle journalled on said boss, and a flexible conduit connecting said nozzle and outlet. 110

In testimony whereof I have hereunto set my hand in presence of two subscribing witnesses.

CHARLES HAROLD SPOONER.
